SKILLET OR SIMILAR ARTICLE

John Caldwell Hampshire, New Rochelle, N. Y.
Application October 28, 1954, Serial No. 32,863

Term of patent 14 years

(Cl. D44—1)

Fig. 1 is an exploded view in perspective of a skillet or similar article, showing my new design;

Fig. 2 is another perspective view thereof with the cover in a closed position; and

Fig. 3 is a fragmentary cross-sectional view taken along line 3—3 of Fig. 2.

I claim:

The ornamental design for a skillet or similar article, as shown.
